UNITED STATES PATENT OFFICE

2,321,452

TEXTILE TREATING APPARATUS

Emil J. Berger, Hatfield, and Howard W. Matthews, Lansdale, Pa., assignors to Dexdale Hosiery Mills, Lansdale, Pa., a corporation of Pennsylvania

Application March 26, 1941, Serial No. 385,238

30 Claims. (Cl. 223—76)

This invention relates to apparatus useful in treating textiles or textile products which, in finishing, require subjection to a vapor medium under pressure for a definite period of time to shape articles such as hosiery, or to set them against subsequent distortion either in use or incident to washing.

The invention constitutes an improvement over a generally similar apparatus which forms the subject matter of a copending application Serial No. 320,656, filed by us jointly on February 24, 1940, the chief aim of the present invention being to render the operation of such apparatus more automatic and therefore more efficient, thereby to preclude the necessity for dependence upon the skill or judgment of the attendants. Another aim of our invention is to make it possible to convert such apparatus for use in drying hosiery and the like.

A further aim of our present invention is to attain the above advantages in apparatus which is compact and of simple construction notwithstanding its automatic operation.

One way in which the foregoing and other important advantages are realized in practice will appear from the following description of the attached drawings, wherein

Fig. 1 shows our improved apparatus in front elevation and arranged for the treatment of hosiery mounted on shaping forms.

Fig. 2 is a fragmentary view on a somewhat larger scale showing the apparatus as it appears from the rear.

Fig. 3 shows the top plan view of the apparatus.

Fig. 4 is an elevation of the apparatus looking toward the right hand end of Figs. 1 and 3.

Figs. 5 and 6 are fragmentary cross sectional views of the apparatus drawn to a still larger scale and taken as indicated respectively by the angled arrows V—V and VI—VI in Fig. 1.

Fig. 7 is a fragmentary detail sectional view taken as indicated by the angled arrows VII—VII in Figs. 3 and 5.

Fig. 8 is a fragmentary detail view looking as indicated by the angled arrows VIII—VIII in Fig. 1.

Fig. 9 is a fragmentary detail sectional view taken as indicated by the angled arrows IX—IX in Fig. 8.

Fig. 10 is a fragmentary detail sectional view taken as indicated by the angled arrows X—X in Fig. 3.

Fig. 11 is a fragmentary view in plan showing one of the collapsible hosiery form supporting carriages of the apparatus in expanded condition.

Fig. 12 is a fragmentary detail sectional view taken as indicated by the angled arrows XII—XII in Fig. 11.

Fig. 13 is a horizontal section of the treating chamber of the apparatus taken as indicated by the angled arrows XIII—XIII in Fig. 1.

Fig. 14 is a fragmentary view in longitudinal section showing the carriage for one set of the hosiery forms in position ready to be transferred into the treating chamber.

Figs. 15 and 16 are views like Figs. 5 and 6 with the door of the treating chamber open.

Fig. 17 shows the apparatus in vertical section and converted for use as a drying machine with the door of the treating chamber partially closed.

Fig. 18 is a fragmentary vertical sectional view corresponding to Fig. 15 of the converted apparatus with the door of the treating chamber fully open.

Fig. 19 is a view like Fig. 18 but with the chamber door partly open as in Fig. 17.

Fig. 20 is a wiring diagram of the electrically actuated devices by which the operation of the apparatus is automatically controlled.

Fig. 21 is a fragmentary view in horizontal section of an alternate embodiment of our invention with its treating chamber closed and containing a group of the hosiery forms.

Fig. 22 is a view generally like Fig. 21 but on a larger scale with the treating chamber open and the hosiery forms withdrawn and being transported into the righthand track section.

Fig. 23 is a fragmentary view in longitudinal section taken as indicated by the angled arrows XXIII—XXIII in Fig. 21.

Fig. 24 is a fragmentary detail sectional view taken as indicated by the angled arrows XXIV—XXIV in Fig. 22.

Fig. 25 is a fragmentary view in cross section taken as indicated by the angled arrows XXV—XXV in Figs. 21 and 23.

Figs. 26 and 27 are fragmentary detail sectional views taken as indicated respectively by the angled arrows XXVI—XXVI and XXVII—XXVII in Figs. 24 and 23.

Fig. 28 is a fragmentary detail view looking as indicated by the angled arrows XXVIII—XXVIII in Fig. 21.

Fig. 29 is a fragmentary view partly in elevation and partly in section taken as indicated by the angled arrows XXIX—XXIX in Fig. 28; and

Fig. 30 is a detail sectional view taken as indicated by the angled arrows XXX—XXX in Fig. 26.

As herein delineated, our improved textile treating apparatus comprises a treating chamber

which is comprehensively designated by the numeral 20, and which as best shown in Figs. 1 and 6, is supported at an elevation above floor level by a substructure 21 formed from standard angle irons. Referring to Figs. 5, 6 and 14, it will be noted that the treating chamber 20 is relatively high and narrow, of rectangular configuration, and exteriorly covered with heat insulating panels 22 at its sides and back. At the front, the chamber 20 has a full size opening 23, which, during the treating periods, is closed by a door 24 which seals fluid tight against packing 25 recessed into a perimetric groove around the door opening. By means of straps shown at 26 (Fig. 7), the door 24 is suspended from carriages 27 provided with rollers 28 which run between vertically spaced pairs of guide rods 29, 30. As shown in Fig. 5, the guide rods 29, 30 are secured in spaced brackets 31, 32 mounted on the top of the treating chamber 20, and extend forwardly beyond said chamber, the corresponding pairs being connected at their outer ends by tie plates 33. The door 24 is locked in closed position by fastening mechanism which includes groups of vertically-spaced, medially-pivoted latches 34 arranged adjacent the opposite vertical edges of the door, and adapted to individually engage fixed keepers 35 adjacent the side edges of the door opening from above with a wedge fit. The latch 34 of the respective groups are connected at their inner ends by universal bars 36 for simultaneous operation. Movable up and down in spaced guides 31, 33 affixed to the outer face of the door 24 is a vertically-arranged slide 39, which, by means of supplemental links 40, is coupled with the universal bars 36.

Above the upper guide 37, the slide 39 is longitudinally slotted as shown at 42 in Figs. 5 and 7 for passage through it of an upstanding cam fin 43 at the forward end of a toothed horizontal rack bar 45, confined to endwise movement in fixed guides 46 and 47 centrally of the top of the treating chamber 20. As shown, the cam fin 43 has an arcuate slot 48 which is engaged by a roller 49 carried at the back of the slide 39. Meshing with the teeth of the bar 45 is a spur pinion 50 which is affixed to a transverse shaft 51 having journal support at its ends in bearings 52, 53 at the top of the chamber 20. The pinion shaft 51 is connected to a speed reduction unit 54 wherewith is associated a reversible electric driving motor 55, said unit and motor being jointly supported by a bracket 56 secured to one side of the treating chamber 20 as shown in Figs. 2, 3 and 4. From Fig. 5, it will be seen that clockwise rotation of the pinion 50 will be attended by outward movement of the rack bar 45 incident to which, by action of the curved slot 48 in the cam fin 43 upon the roller 49 on the slide 39, the latter will be depressed and through the links 40 cause disengagement of the door latches 34 from the keepers 35. Upon advance of the cam fin 43 to the point where the roller 49 will be positioned in the horizontally offset rear terminal portion 48x of the slot 48; the now unlatched door 24 will be moved outward to the open position shown in Figs. 15, 16, its top coming to rest with the front rollers 28 of the carriages 27 engaging adjustable inwardly projecting stops 33a on the tie plates 33 which connect the respective pairs of carriage guiding track rods 29, 30. When, on the other hand, the direction of rotation of the pinion 50 is reversed, the door 24 will first be moved to closed position due to temporary detainment of the roller 49 on the slide 39 within the offset terminal notch 48x of the slot 48 in the cam fin 43. When,

however, the door 24 has reached its closed position in abutment with the sealing strip 25 and as the rack bar 45 continues in its inward movement, the roller 49 will be forced to travel upward in the slot 48 of the cam fin 43, with attendant lifting of the slide 39 and swinging of the door latches 34 simultaneously to re-engage the keeper 35. Suitably supported respectively on one of the upper door carriage guide rods 29 and on the top of the chamber 20 are reversing limit switches 57, and 58 for controlling the operation of the electric motor 55 in a manner also explained hereinafter, the roller on the actuating arm 59 of the switch 57 being located in the path of a projection 57x on one of the door carriages, and the roller on the actuating arm 60 of the switch 58 being in the path of the upper rounded edge of said cam fin 43.

In the present instance, steam under pressure is employed as a treating medium, the same being delivered from a suitable source of supply (not illustrated) through a pipe 62, see Figs. 2 and 6, in which a trap 63 is interposed and also a hand valve 64. As shown, the pipe 62 is extended as at 65 to a double acting supply and exhaust valve 66 which may be of any approved type and which is adapted to be electrically operated through the medium of a solenoid 67. For protection, the valve 66 and its actuating means 67 is enclosed in a casing 68 mounted on the back of the treating chamber 20. Extending from the valve 66 into the treating chamber 20 near the bottom is a branch pipe 69 by way of which the steam is conducted into said chamber. Leading downwardly from the valve 66 is a pipe 70 by which the steam is exhausted from the chamber after each treating period. As shown in Fig. 6, the bottom 71 of the treating chamber 20 is depressed to promote drainage of condensation into an outlet 72, which, through a pipe 73, communicates with a trap 75. From this trap 75, see Fig. 2, leads another pipe 76 by which the condensation is carried off to a suitable point of disposal (not illustrated). As further shown in Fig. 6, a horizontally-arranged perforated plate 77 supported by upstanding posts 78 within the lower part of the treating chamber above the level of the steam inlet pipe 69, serves as a means to protect the hosiery while it is treated in the chamber, against the direct action of the steam issuing from said pipe. The door 24 is preferably constructed from heavy plate metal so as to be rigid against bending and capable of bearing uniformly all around against the resilient sealing strip 25 to insure against escape of steam from within the chamber 20 during the treatment. Since the door 24 is directly exposed to the steam it becomes very hot, and in order to preclude injury to the attendant of the apparatus, there is mounted upon the outer side of the door in spaced relation therewith a safety shield 80 which may be formed of asbestos board or other suitable heat insulating material, said guard being supported by spacing pins 81 with provision of an interval for the accommodation of the door latch operating mechanism. Sustained by an angle bracket 82 at the back of the door 24 near the top, is a thermostat 83. Connected into one side of the treating chamber is a pressure relief or safety valve 84 which will yield in case, for some reason or other, the pressure should rise beyond a predetermined limit; and on the door 24, at the front, are mounted direct reading temperature and pressure gauges which are shown at 85 and 86 in Figs. 1 and 3.

Extending longitudinally of the front of the

treating chamber 20 with its top slightly above the level of the chamber floor is a framework 87 which is preferably constructed from structural iron. As shown, the opposite end portions 88 and 89 of the framework extend to equal distances beyond opposite sides of the treating chamber 20, with laterally-spaced pairs of upper longitudinals 90, 91 and 92, 93 respectively constituting guide ways or tracks for lengthwise expandable carriages 94 and 95, each of which supports a series of profile shaping forms 96 for hosiery, one such carriage being adapted to occupy its track, while the other occupies the chamber 20 and vice versa. The carriages 94 and 95 are identical in construction so that the description which is about to follow for one of them will also hold for the other.

The carriage 94 is in the form of a lazy tong composed of link bars 97 and 98 whereof respective pairs are interpivoted at their centers and which are pivotally connected at their ends to corresponding bars of adjacent pairs, the two links at the righthand end of said carriage being connected by a slotted tie link 99. The common connecting pivots 100 for the bars 97, 98 are in the form of cap bolts, whereof the shanks respectively engage into the tops of vertical stems 101 of square cross section which pass downwardly with a sliding fit between the track rails 90, 91 at the top of the extension 88 of the framework 87. Freely revolvable about laterally-projecting screw studs 102 at opposite sides of the stems 101 are rollers 103 which run on the top surfaces of the track rails 90 and 91 and so support the respective pairs of the carriage cross bars 97, 98 for mobility. The stems 101 are held against upward displacement by collars 104 secured to reduced cylindrical projections at their lower ends, said collars underreaching the inner pendant flanges of the track rails 90 and 91 as clearly shown in Figs. 10 and 12. Extending from the left hand end block 101a of the carriage longitudinally of the carriage 95 is a cylindric tongue 105 which passes into axially aligned apertures in the other blocks (except for a few at the righthand end of the carriage) when the carriage is collapsed as exemplified in Fig. 14, thereby holding the latter steady during subsequent transfer. Each hosiery shaping form 96 is provided on one side near the bottom with a block 106 from which a dowel pin 107 extends downwardly and engages into a boss 108 on one of the bars 97 of the carriage 94, each form being held in alignment with its supporting bar between a pair of fixed upstanding lugs 109, 110, on said bar. In order that the hosiery may be readily mounted and removed from the forms, the carriage 94 is expanded lengthwise as shown in Figs. 1 and 3 while at rest on the tracks 90, 91. However, before the loaded forms are placed in the treating chamber 20 in a manner later explained, the carriage is collapsed so as to occupy a minimum amount of space. Accordingly, a treating chamber of correspondingly small dimensions may be used and the treatment carried out with economic use of steam.

The actuation and shifting of the carriages 94, 95 is automatically effected by a progressing or conveying element in the form of an endless chain 112 which extends lengthwise of the framework 87 in the medial vertical longitudinal plane of the latter, and which is trained about sprocket wheels 113, 114 whereof the shafts are journalled in bearings 115, 116 at the extreme ends of the framework extensions 88, 89. Journalled centrally of the framework 87, is a transverse shaft 117 whereon is mounted a sprocket wheel 118

which is undertraveled by the upper run of the sprocket chain 112 at the region where said chain is diverted downwardly after having traveled over a pair of idler wheels 119, 120. The shaft 117 is driven through a sprocket chain connection 121, from a speed reduction unit 122 which is in turn driven by another chain connection 123 by a reversible electric motor 125, said speed reduction unit and motor being supported upon a shelf or table 126 in the lower central part of the substructure 21.

As shown in Fig. 1, the conveyor sprocket chain carries studs 127, 128, the first of which is adapted to engage (see Fig. 14) a pendant projection 129 on the endmost stem 101a associated with the carriage 94 the other stud being adapted to cooperate in the same way with a dependent projection 130 on the lefthand endmost stem 101a of the carriage 95.

15 The projection 129 is pivotally connected at its upper end to the stem 101a, and provided with a cross pin 131 at the bottom end which is adapted to engage in the interval between the laterally spaced lugs 127 as shown in Fig. 6, and so hold said projection against swinging laterally during carriage transfer. When the sprocket chain 112 moves in the direction indicated by the arrow in Fig. 14, the studs 127 thereon engage behind the pendant projection 129 of the stem 101a and move the latter in the same direction. At this time, however, the lefthand end stem 101 of the carriage 94 is restrained against movement through frictional engagement of the laterally projecting stud 132 thereon (see Fig. 10), 20 with a small wedge cam rise 133 affixed to the top of the guide rail 90. Under the action of the cam lug 133 (Fig. 10) a slight skewing of the lefthand end of the carriage is caused and the lefthand end stem 101 thereby somewhat frictionally bound between the track rails 90, 91. Thus, under these circumstances, the carriage is completely collapsed to the condition shown in full lines in Fig. 14, and transferred bodily into position centrally of the front of the treating 25 chamber 20 when the door 24 is in retracted or open position, see Figs. 15 and 16, onto a pair of supplemental track rails 134, 135 supported by an angle bracket 136 at the back of the door. The last described position of the carriage 94 is determined by encounter of the lug 132 on the lefthand end stem 101 with a stop 137 on the supplemental track rail 134 at the back of the door, a similar stop lug 138 being provided to serve in a like capacity for the carriage 95. For determination of proper alignment of the supplemental tracks 134, 135 with the fixed tracks 90, 91 and 92, 93 in the interval between the contiguous ends of the latter, adjustable stop screws 139 (Figs. 3 and 6) have been provided for the lower 30 end of the door 24, said stop screws being supported in a yoked bridging bar 140, which, at opposite ends, is rigidly secured to the fixed track rails 91 and 93, see Figs. 1 and 6. As shown, the stops 139 are engaged by heads 141 at the outer ends of the lower spacers 81 which support the protective shield 80 on the door 24. A spring 142 interposed between a pair of adjacent intermediate stems 101 of the carriage 94 (Fig. 14) is compressed after the carriage is arrested by the stop 137 and yields to permit the lugs 127 on the sprocket chain 112 to pass beyond the pendant projection 129 on the block 101a, whereupon said spring immediately reacts to slightly expand the carriage. As a consequence, the projection 129 is 35 restored to the dot and dash line position of Fig.

14 in readiness to be reengaged by the lugs on the reverse movement of the chain 112 for transport of the carriage back onto the framework extension 88. As the carriage 94 is moved outward on the extension 88, the righthand end stem 101x encounters a leaf spring stop 143 (Figs. 8 and 14) which yields to allow the lugs 127 to pass beyond the projection 129, and which will immediately thereafter act to reposition said stud. The operation of the motor 125 by which the conveyor chain 112 is actuated is controlled by reversing limit switches 144 and 145 which are fixedly supported respectively at opposite ends of the framework extensions 88, 89, see Fig. 1. As shown, the roller arms 146, 147 respectively of the switches 144, 145 are in the path of laterally projecting lugs 147 and 148 on the chain 112, see Figs 8 and 9.

In addition to the electrical devices already described, other automatic control devices are employed, to wit, a pressure responsive switch 150 and an electric control timer 151 which are mounted at the left side of the treating chamber 20, starting push buttons 152, 153 for the conveyor motor 125 which are located at the front of the framework adjacent opposite ends of the yoked bar 138, a safety stop push button switch 155 which is located on said framework immediately below the push button switch 152, a relay 156 in circuit with button switches, a door motor control switch box 157 and a conveyor motor control switch box 158, which latter three are mounted to the right side of the chamber 20. These devices, together with a line starter box 160 are all symbolized and respectively identified comprehensively by the same reference characters in the wiring diagram of Fig. 20.

In order to enable utilization of the apparatus as an automatic drying machine, we have made the further provisions about to be described. Disposed within the chamber 20, Figs. 2 and 17 at the rear is a blower fan 165 whereof the shaft 166 passes through a stuffing box 167 and is connected to a driving motor 168 supported by a fixed bracket 169 at the exterior. Immediately forward of the fan 165 is a vertically-arranged bank of heating coils 170 whereof the supply pipe 171 connects at 172 (Figs. 2 and 4) with the main steam supply pipe 62 beyond the valve 64, and has interposed in it a separate hand valve 173. The exhaust pipe 175 of the heating coil 170 may lead to any suitable point of disposal. In the use of the apparatus as a dryer, it is desirable to admit a definite amount of fresh air into the chamber 20, and for this reason the door 24 is never fully closed, that is to say, its inward movement is limited to the position shown in Fig. 17. This limit position is determined by application to the fin cam 43, see Figs. 18 and 19 of a bar extension 176 whereby the roller arm 60 of the switch 58 is actuated somewhat earlier than before to prevent full door closure incident to automatic operation of the apparatus otherwise as previously explained. As shown the bar extension 176 has a pendant portion 177 which slidably fits within a vertical guide 178 on the fin cam 43. A retractable spring pressed pin 179 on the guide 177 is selectively engageable with two vertically-spaced socket holes 180, 181 in one edge of the pendant portion 177 of the bar extension 176 so that the latter may be locked in the upper position in which it is shown, or in a lowered position where it will be inoperative incident to

first described use of the apparatus. As shown in the wiring diagram of Fig. 20, the fan motor 168 is connectable to the power circuit by means of a hand switch 182. Thus, to convert the apparatus into a drying machine, it is necessary only to close the valve 64, to open the valve 173, elevate the bar extension 176 as in Figs. 18 and 19, and to throw the switch 182 for the fan motor 168.

10 When the apparatus is to be used for treatment of the hosiery with steam under pressure, the fan switch 186 is thrown to the position shown in Fig. 20, the hand valve 64 opened and the hand valve 173 closed. With this preparation, and assuming the parts to be in the positions shown in Figs. 5 and 6 with the form carrier 94a in the chamber 20, and with the form carrier 95a expanded on the frame extension 89 in readiness to be loaded with fresh stockings, the operation of the apparatus is as follows: Under the control of the timer switch 151 and after the lapse of the required treating period, the solenoid 67 is energized to actuate the valve 66 to cut off supply of steam to the chamber 20 and to permit exhausting thereof. Upon release of all the steam, the pressure responsive valve switch automatically closes, completing the circuit to the door control box 157 to effect closure of the circuit through the motor 55 with the result 20 that the rack 45 is moved outward. At the initiation of this movement, the door fastening mechanism is unlocked by movement of the slide 39 induced through coaction of its roller 49 with the curved slot 48 in the fin cam 43 to release the door 24. Finally, when the roller 49 occupies the rest notch 48 in the fin cam 43, the door 24 is carried along with the rack 45. As the door 24 nears full open position, the limit switch 57 is automatically actuated through encounter of its roller arm 59 with the projection 57x, whereby current to the motor 55 is interrupted, the door finally coming to rest in the position in which it is shown in Figs. 15 and 16 with the supplemental tracks 134, 135 thereon 30 in line with the track rails of the end extensions 88, 89 of the framework. An operative cycle of the apparatus is thereby completed. Then after having loaded the carriage 95, the operator presses the push button 152 to establish current flow to the motor 125 for actuation of the carriage progressing chain 112. Immediately progression leftward in Fig. 1 of the two form carriages 94 and 95 is begun in consequence of coaction of the projections 129 on them with the projections 127, 128 on the chain 112. Accordingly, the carriage 95 is drawn from the supplemental tracks on the door 24 onto the fixed track extension 89. The carriage 94, however, due to being restrained by the wedge cam 133 is collapsed before being bodily drawn from the fixed track extension 88 onto the supplemental tracks on the door. Later, as its progress continues, the carriage 95 is expanded by the action of the wedge block 134 upon its stem 101x. As the carriage 95 nears the limit of its leftward travel, the switch 145 is operated and reversed and the circuit through the motor 125 opened to stop movement of the chain 112. Also at the same time, door control switch 158 is actuated to start the motor 55 (reversely) as a result of which the door 24 is moved inward and the loaded carriage placed within the chamber 20. The door 24 is locked upon reaching its fully closed position through actuation of the fasten- 40

ing mechanism by the influence of the cam slot 48 in the fin 43 upon the roller 48x on the slide bar 39, and the switch 57 operated by the fin cam to stop the motor 55. Thereupon, the timer 151 again acts to automatically control the period of treatment and opening of the door 24, with completion of another operative cycle. After the carriage 95 has been loaded, the attendant presses the lefthand button 153 to start the next cycle for movement of the conveyor rightward incident to which the carriage 95 is collapsed and advanced to the tracks on the door, while the carriage 94 is withdrawn from the door and returned in expanded condition to the track extension 88 for loading.

The automatic operation of the apparatus when used as a dryer is exactly the same as above described, and for conversion merely requires, as hereinbefore pointed out, closing of the valve 64, opening of the valve 173, reverse positioning of the hand switch 182, and raising of the fin cam extension to the position shown in Figs. 18 and 19.

In the alternative embodiment of our invention featured in Figs. 21-30, a horizontal toothed rack 112a is substituted for the form carriage advancing chain 112 of the first embodiment. As shown in Fig. 25, the rack bar 112a rests upon a pair of transversely-spaced fixed rails 185, 186 suitably incorporated in the framework of the apparatus (see Figs. 21-24 and 27 also), and is held down by top plates 187 and 188 secured by bolts 190 to lugs 191 on the framework, said rack having a pendant rib 192 confined to guide slot afforded jointly by said bars. The teeth of the rack 112a mesh with a driving gear 118a on the shaft of a speed reduction unit 122a built into an electric motor 125a which corresponds to the motor 125 of the first embodiment. Affixed to the rack 112a adjacent its opposite ends (Fig. 23) are guides 193, 194 for vertically slideable projections in the form of plungers 195, 196 whereof the upper ends are rounded. Rollers 197, 198 projecting laterally from the lower ends of the plungers 195, 196 ride on another fixed longitudinally-extending rail 199 which is co-extensive with the framework and depressed as at 200 centrally of the front Fig. 23 of the treating chamber 20a. As shown, the depression 200 merges with the main portion of the rail 199 through cam roundings 201, 202 which are overhung by supplemental guard cam pieces 203, 204.

It will also be noted that the form carriages 94a, 95a illustrated in connection with the alternative embodiment of our invention are of modified construction. In this instance, the forms 96a are individually supported with capacity for removal by swivel blocks 205 each of which has an upstanding lug 109a with a pair of headed studs 206 projecting laterally from it; while the corresponding form 96a has upward notches 207 in its lower edge to clear the shanks of said studs, see Figs. 28-30. Pivoted on each swivel block 205 is a wedge handle 208 with notches 209 in its lower edge which are also adapted to clear the stud shanks. When the handle 208 is swung downward from the position shown in Fig. 28, it functions as a wedge between the heads of the studs 206 and the contiguous face of the form 96a as shown in Fig. 29 to firmly clamp said form against the lug 109a and to hold it firmly in position on its supporting block. Extending horizontally from one end of each swivel block 205 is a rod 210 which serves a purpose later on explained. The central pivots for the 75

cross bars 97a, 98a of the lazy tong form carriages 94a, 95a are integrally formed with the swivel blocks 205 as pendant cylindric stems 101a, 109y which pass downward through central apertures in said bars as shown in Fig. 30. From the latter illustration it will be further noted that the bars 97a of the carriages 94a, 95a rest directly on the spaced track rails 90a, 91a, 92a, 93a of the end extensions 88a, 89a of the framework 87a. Pinned to the bottom of each of the stems 101a is a retainer 211 with diametral wings 212 which underreach the track rails 90a, 91a, 92a, 93a to confine the swivel block 205, and with a central boss 213, which fits upward into the interval between said rails. As instanced in Fig. 24, the stems 109y of the outermost form supporting bars 205 of the carriages 94a, 95a are longer than the others, and have collars 214 secured to them below the retainers 211. These collars 214 are recessed at the bottom for engagement respectively by the rounded upper ends of the plungers 195, 196 on the rack bar 112a. The form carriages 94a are moreover provided at their inner ends with supplemental bars 215 which reach forwardly beyond the others, see Figs. 21 and 22. The projecting end of the supplemental bar 215 of the carriage 94a is turned downward as at 216 in Fig. 21, and that of the carriage 95a is turned upward as at 217 for coaction respectively with fixed oppositely-arranged hook lugs 218, 219 at different levels at the opposite ends of the supplemental track at the back of the door 24a of the treating chamber 20a, see Figs. 22, 23 and 25. Fulcrumed on the framework extensions 88a, 89a are horizontal cam levers 220, 221, see Figs. 23 and 26, which are adapted to be wiped by the collars 214 on the carriages 94a, 95a and, when so actuated, to operate limit switches 144a and 145a corresponding to the limit switches 144, 145 of the first embodiment. In all other respects, the alternative construction is identical with the first embodiment, and therefore, in order to obviate repetitive description, all other parts which are shown but which have not been specifically referred to, are identified by the same reference numerals previously employed, except for further characterization, in each instance, by addition of the letter *a* for convenience of more ready distinction.

In Fig. 21 the carriage 94a is collapsed and positioned on the supplemental tracks 134a, 135a and is within the chamber 20a, its collapse and exact position having been determined through engagement of the projecting end of the supplemental cross bar 215 with the stop lug 219 and by the engagement of the collar 214 on its outermost stem 109y with a stop 222 centrally of a cross member 223 beneath the tracks 134a, 135a on the door 20a, see Fig. 22 and 24 also. A stop (not shown) similar to the stop 222 is of course likewise provided for the carriage 95a. During the collapse of the carriage 94a, uniform positioning of the forms 96a was predetermined through encounter of the rods 210 on the swivel blocks 205 with the heads 225 of the pivots which connect the cross bars 97a, 98a at one side of the carriage. Just as the carriage 94a has reached its final position upon the tracks on the door 24a, the plunger 195 was fully withdrawn from engagement with the collar 214 under the influence of the guard cam piece 203 as in Fig. 23, the carriage having thereby been released to permit door closure. In Fig. 22, the carriage 94a is being moved rightward on

the fixed track extension 88a as a consequence of the reengagement of the plunger 194 on the moving gear rack 112a with the collar 214 on the stem 109y of its outermost form supporting bar 98a, most of it being still on the door track rails. At the same time the carriage 94a is being gradually expanded through friction of its cross bars 91a with the track rails, and as a consequence of, the restraint temporarily imposed upon its supplemental end bar 215 by the hooked stop lug 219. While the foregoing is taking place, the other carriage 95a is, of course, being collapsed and moved toward the chamber 20a. As the carriage 94a reaches the outer limit of its travel on the track extension 88a, the switch 144a is actuated by the liner 220 as in Fig. 26 to shut off current supply to the conveyor motor 125a, by which time the other carriage 95a has been delivered collapsed on the door tracks. It is to be understood that the timing and control of the operative cycle of the modified embodiment is exactly the same as described in connection with the first embodiment. When the carriages 94a and 95a are expanded on the track extensions 88a, 89a, it will be evident that the forms 96a can be turned about the swivel centers whereby dismounting and mounting of the stocking is greatly facilitated.

While we have shown and described our invention in a form especially suited for the treatment of hosiery, it can be readily adapted for the treatment of other products or materials by resorting to other modifications within the scope of the appended claims.

Having thus described our invention, we claim:

1. Apparatus for treating textile products, comprising a treating chamber with a door at the front thereof; space aligned horizontal stationary track sections extending lengthwise of the front of the chamber and respectively beyond opposite sides thereof; an auxiliary track section mounted on the back of the door and capable of registry with the stationary track sections in the interval between the latter; carriages for the textile products individually associated with the two stationary track sections; and reversible progressing means operative to effect transfer of one carriage from one stationary track section to the auxiliary track section on the door and transfer of the other carriage from the auxiliary track section to the other stationary track section, and vice versa.

2. Apparatus according to claim 1, for treating textile products in which the reversible progressing means includes a transfer element movable lengthwise of the two stationary track sections; means on said transfer element for respectively engaging the two carriages; and a reversible drive for actuating the transfer element.

3. Apparatus according to claim 1, for treating textile products in which the reversible progressing means includes a transfer element movable lengthwise of the two stationary track sections; means on said transfer element for respectively engaging the two carriages; a reversible electric motor for actuating the transfer element; a manual starting switch in circuit with motor; and limit switches also in circuit with the motor and actuated by the transfer element to automatically stop the motor when said element has reached the limit of its movement in either direction.

4. Apparatus according to claim 1 for treating textile products in which the reversible progress-

ing means includes an endless strand element which extends lengthwise of the two stationary track sections and which is trained about supporting wheels at opposite ends of the apparatus, projections on the strand element for respectively engaging the two carriages, and a reversible drive for actuating the conveyor element.

5. Apparatus according to claim 1 for treating textile fabrics, in which the reversible transfer means includes a toothed bar confined to back and forth endwise movement lengthwise of the two stationary track sections, projections on the bar for respectively engaging the two carriages, and a reversible drive for actuating said bar.

10 6. Apparatus according to claim 1, for treating textile products including reversible operating means for opening and closing the door; and automatic means actuated by the progressing means for controlling the door operating means.

20 7. Apparatus according to claim 1, for treating hosiery and the like, in which the carriages are expandable and support a plurality of mounting forms for the hosiery; and including means automatically operative incident to carriage transfer for collapsing that carriage which is being moved onto the track on the door and of expanding that carriage which is being moved from the door onto its stationary track.

30 8. Apparatus for treating textile products such as hosiery and the like comprising a treating chamber; a track leading to the chamber; an expandable carriage supporting a plurality of hosiery forms and movable along the track; means for moving the carriage to and from the chamber; means in the direct path of the carriage as it is moved along the track to the chamber for automatically collapsing it, and for automatically expanding it as it is moved away from the chamber on the track.

35 40 9. Apparatus for treating textile products such as hosiery and the like, comprising a treating chamber; a track extending beyond opposite sides of the chamber; a pair of expandable carriages respectively supporting plural mounting forms; reversible advancing means operative to advance one carriage from the chamber to one end of the track while advancing the other carriage from the other end of the track to the chamber; and means automatically operative incident to movement of the advancing means to collapse the carriage which is being advanced to the chamber and to expand the other carriage on the track.

45 50 10. Apparatus for treating textile products, comprising a treating chamber with a door; door operating means including a reversible electric motor and limit reversing switches to stop the motor when the door reaches its open and closed positions respectively; valve means for admitting and exhausting fluid treating medium to and from the chamber; electric actuating means for the valve means; a track leading to the chamber; a carriage for the textile products movable along the track to and from the chamber, means for progressing the carriage as aforesaid; means for actuating the progressing means including a reversible electric motor; a manual starting switch to close a circuit containing the last mentioned motor for advance of the carriage on the track to the chamber; a reversing switch automatically actuated when the carriage reaches the chamber to stop the motor; means in circuit with the latter switch for thereafter completing a circuit containing the door motor to effect closure of the door; automatic timing means operative after the lapse of the required treating period upon

closing of the door to effect actuation of the valve means thereby to shut off the supply of treating medium and permit its exhaust from the chamber, and to restart the door motor for opening the door; another manual switch for restarting the motor of the progressing means to move the carriage from the chamber; and another switch actuated when the carriage has been retracted on the track to its original position to automatically effect stoppage of the motor last mentioned.

11. Apparatus for treating textile products, comprising a treating chamber with a door at the front thereof; door operating means; spaced aligned horizontal stationary track sections extending lengthwise of the front of the chamber and respectively beyond opposite sides thereof; an auxiliary track section mounted on the back of the door and adapted to register with the stationary track sections in the interval between the latter when the door is open; carriages for the textiles respectively associated with the two stationary track sections; reversible progressing means for transferring the carriage from one stationary track section to the auxiliary track section on the door while transferring the other carriage from said auxiliary track section to the other stationary track section, and vice versa; automatic means for controlling the door operating means and the progressing means to carry out an operative cycle by which one of the carriers is advanced from its track to the auxiliary track on the door, the door is closed with the carriage thereon within the chamber, and, after lapse of the required treating period, the door is restored to open position; and manual means for initiating each such cycle.

12. Apparatus according to claim 11, in which the door operating means and the progressing means are electrically actuated, and wherein the automatic control means includes a system of switches in circuit with the door operating and conveyor means.

13. Apparatus for treating textile products, comprising a treating chamber with a door at the front thereof; door operating means; valve means for admitting and exhausting fluid treating medium to and from the treating chamber; spaced aligned horizontal stationary track sections extending lengthwise of the front of the chamber and respectively beyond opposite sides thereof; an auxiliary track section mounted on the back of the door and adapted to register with the stationary track sections in the interval between the latter when the door is open; carriages for the textile products respectively associated with the two stationary track sections; reversible progressing means for transferring the carriage from one stationary track section to the auxiliary track section on the door while transferring the other carriage from the auxiliary track section to the other stationary track section, and vice versa; automatic means for controlling the door operating means, the progressing means and the valve means to carry out an operative cycle by which one of the carriers is advanced from its track to the auxiliary track on the door, the door is closed with the carriage thereon within the chamber, the valve is actuated for admission of treating medium into the chamber, and, after lapse of the required treating period, the valve is again actuated to shut off the supply of treating medium and the door is restored to open position; and manual means for initiating each such cycle.

14. Apparatus according to claim 13, in which the door operating means, the valve means and

the progressing means are electrically actuated, and wherein the automatic control means includes a system of switches in circuit with the door operating means, the valve means and the conveyor means.

15. Apparatus for treating textile products, comprising a treating chamber with a door at the front thereof; door operating means; door fastening means; valve means for admitting and exhausting fluid treating medium to and from the treating chamber; spaced aligned horizontal stationary track sections extending lengthwise of the front of the chamber and respectively beyond opposite sides thereof; an auxiliary track section mounted on the back of the door and adapted to register with the stationary track sections in the interval between the latter when the door is open; carriages for the textile products respectively associated with the two stationary track sections; reversible progressing means for transferring the carriage from one stationary track section to the auxiliary track section on the door while transferring the other carriage to the other stationary track section, and vice versa; automatic means for controlling the door operating and latching means, the progressing means and the valve means to carry out an operative cycle by which one of the carriers is advanced from its track to the auxiliary track on the door, the door is closed with the carriage thereon within the chamber, the fastening means is thereupon actuated to lock the door, the valve is next actuated for admission of treating medium into the chamber, and, after lapse of the required treating period, the valve is actuated to shut off the supply of the treating medium, the fastening mechanism is next again actuated to release the door, and finally the door is restored to open position; and manual means for initiating each such cycle.

16. Apparatus for treating textile products comprising a treating chamber with a door; door latching means including a latch operable by a vertical slide on the door; a carriage from which the door is suspended; a guide track above the chamber for the carriage; door operating means including a member confined to endwise back and forth movement above the chamber in the direction of carriage movement, and reversible drive means for the member; a cam with a stop end on said member to cooperate with a projection on the latch actuating slide, whereby the member is moved outward, the fastening mechanism is actuated to release the door before the latter is carried along to open position, and whereby, when the member is moved inward, the door is closed before setting of the fastening means; and automatic control means operative to render the drive means for the member inactive when the door has reached its open position or its closed position.

17. Apparatus according to claim 16, in which the member has gear teeth; in which the drive means includes a reversible motor with a pinion in mesh with the teeth on said member; and in which the automatic control means includes a pair of reversing limit switches in circuit with the motor.

18. Apparatus according to claim 25 for treating textiles, in which the drive for the door operating means includes a reversible electric motor, and in which the means actuated by the progressing means for controlling the door includes reversing limit switches in circuit with the motor.

19. Apparatus for treating textile products such as hosiery and the like, including a treating chamber; a track leading to the chamber; an ex-

pansible lazy tong carriage mounted on the track and supporting hosiery forms on its interpivoted cross bars; a reversible progressing element with a projection engageable with one end of the carriage to advance the carriage along the track to and from the treating chamber; and fixed means along the track for temporarily restraining the other end of the carriage to determine collapse thereof when it is moved to the chamber and expansion thereof when it is being withdrawn from said chamber.

20. Apparatus for treating textile products such as hosiery and the like, including a treating chamber; a track leading to the chamber; an expansible lazy tong carriage frictionally supported on the track and supporting hosiery forms on its interpivoted cross bars; and a reversible progressing element for advancing the carriage, said element having means for engaging the carriage only at one end, so that by frictional action between the carriage bars and the track, the carriage is automatically collapsed as it is advanced to the chamber, and automatically expanded when it is withdrawn from the chamber.

21. Apparatus according to claim 20 for treating textile products such as hosiery, in which the progressing element is in the form of a toothed gear rack driven by a reversible intermeshing pinion.

22. Apparatus according to claim 27 for treating textiles, including normally inoperative heating means within the chamber, and control means whereby the heating means may be made to function when the apparatus is utilized for drying.

23. Apparatus for treating textile products, comprising a treating chamber with a door; operating mechanism with a reversible drive therefor, for opening and closing the door; door fastening means; means actuated by the door operating mechanism to release the fastening means prior to door opening, and to re-engage said fastening means during actuation of the door operating mechanism in door closing; and means actuated by the door operating mechanism to automatically stop the drive when the door reaches its full open and full closed positions respectively.

24. Apparatus for treating textiles, comprising a treating chamber with a door; door operating mechanism with a reversible drive therefor; a carriage for the textiles; a track for the carriage leading from a loading station to the chamber; carriage propelling means with a drive therefor; manual control means for starting the propelling drive means; means actuated by the propelling means upon arrival of the carriage at the chamber for starting the drive of the door actuating mechanism to effect door closure; means actuated by the door operating mechanism when the door reaches closed position to stop the drive therefor; timing means set into action by the door operating mechanism as the door is closed; means actuated by the timing means upon lapse of the required treating period, for re-starting the drive of the door operating mechanism to effect opening of the door; and means actuated by the door operating mechanism when the door reaches its open position to stop the drive for said door operating mechanism.

25. Apparatus for treating textiles, comprising a treating chamber with a door; door actuating mechanism with a reversible drive therefor; a track leading from a loading station to the chamber; a carriage for the textiles supported on the track; progressing means with a drive

therefor, for advancing the carriage from the loading station to the chamber; means actuated by the progressing means upon arrival of the carriage at the chamber for starting the drive of the door operating means to effect door closure; and means actuated by the door operating mechanism to stop the drive of the latter when the door is fully closed.

26. Apparatus for treating textile products such as hosiery and the like, including a treating chamber; a track leading from a loading station to the chamber; an expansible lazy tong carriage on the track supporting hosiery forms on its interpivoted cross bars; progressing means for moving the carriage along the track to and from the treating chamber; reversible drive means for the progressing means; and means in the path of the carriage to collapse it as it is being moved to the chamber, and to expand it as it is being withdrawn from the chamber.

27. Apparatus for treating textiles, comprising a treating chamber with a door; inlet and outlet valves for admitting and exhausting fluid treating medium, such as steam, under pressure into and from the chamber; means for circulating the atmosphere within the chamber; door operating mechanism with a drive therefor; means for starting the drive for movement of the door by its operating mechanism ordinarily to full closed position after placement of the textiles within the chamber; means actuated by the door operating mechanism upon closure of the door to stop the drive, to open the inlet valve and to close the outlet valve; and means enabling conversion of the apparatus for drying purposes including a manually operable valve means for shutting off the supply of the steam to the inlet valve, and auxiliary means associated with the door operating mechanism for determining earlier stoppage of its drive to leave the door partly open for admission of air into the chamber.

28. Apparatus for treating textile products, comprising a treating chamber with a door; door operating mechanism with a drive therefor; inlet and outlet valves for respectively admitting and exhausting fluid treating medium into and from said chamber; mechanism for actuating the valves; timing means automatically operative upon the lapse of the required treating interval after closing of the door and admission of treating medium into the chamber, to effect actuation of the valve actuating means for shutting of the inlet valve and opening of the outlet valve, and thereafter initiating starting of the drive of the door operating mechanism for movement of the door to open position; and means automatically actuated by the door operating mechanism when the door reaches full open position to stop said drive.

29. Apparatus for treating textile products, comprising a treating chamber with a door; door operating mechanism with a drive therefor; door fastening means; means associated with the door operating mechanism for releasing the fastening means prior to opening of the door by said mechanism; inlet and outlet valves for respectively admitting and exhausting fluid treating medium into and from the chamber; actuating means for the valves; timing means automatically operative upon the lapse of the required treating interval after closing of the door and admission of treating medium into the chamber, to effect actuation of the valve actuating means for shutting of the inlet valve and opening of the outlet valve, and thereafter to initiate starting of the

drive of the door operating mechanism for unfastening of the door and movement of the door to open position; and means automatically actuated by the door operating mechanism when the door reaches full open position to stop said drive.

30. Apparatus for treating textiles, comprising a treating chamber with a door; means for circulating the atmosphere within the chamber; door operating mechanism with drive means therefor; a carriage for the textiles; conveying means for moving the carriage from a loading station to a position at the door opening of the

treating chamber in readiness to be displaced into said chamber as the door is closed; and means automatically actuated by the conveying means to start the drive means for moving the door toward closed position upon delivery of the carriage at the door opening of the treating chamber; and means controlled by the door operating mechanism to stop the drive before the door is fully closed so that fresh air is constantly admitted into the chamber during the treatment.

EMIL J. BERGER.
HOWARD W. MATTHEWS.
